P. ALIDJIADIS

COKE OVEN

Filed April 11, 1923

FIG. 1.

FIG. 2.

PARASCO ALIDJIADIS

Inventor

By: Julian J. Wittel,
His Attorney.

UNITED STATES PATENT OFFICE.

PARASCO ALIDJIADIS, OF NEW YORK, N. Y.

COKE OVEN.

Application filed April 11, 1923. Serial No. 631,446.

To all whom it may concern:

Be it known that I, PARASCO ALIDJIADIS, a citizen of Turkey, and residing at New York city, county and State of New York, have invented a new and useful Improvement in Coke Ovens, of which the following is a specification.

This invention relates to coke ovens and has for its main object to provide an oven in which the highest quality coke may be produced.

Another object of this invention is to provide a coke oven which can be built with a small amount of expense, which will use the heat of its fuel with the highest degree of efficiency and finally which can produce the highest quality of coke from inexpensive raw materials, like small coal, coal-dust and the like.

With the above mentioned and other objects in view, my invention mainly resides in building the coke oven in three superimposed stages, the lowest stage of it being an inexpensive common furnace to burn cheap coal which produces heat for the next stage wherein the heat of the gases of said furnace is used to produce a lower quality preliminary product and finally, the third stage which is the coke oven proper, being charged with coal-dust or small coal in a wet condition and having heating flues in its walls adapted to transmit the remaining useful heat in the gases of the furnace to the charge of said oven whereby said charge will be slowly coked at a relatively low temperature.

For a full description of the invention and the merits thereof and also to acquire a knowledge of the details of construction of the same for effecting the various results mentioned hereinbefore, reference is to be had to the following description and accompanying drawings.

While the essential and characteristic features of the invention are susceptible of modification, still the preferred embodiment of the invention is illustrated in the accompanying drawings, in which:

Figure 1 is a sectional elevation of my three stage oven;

Figure 2 is a front view of the same.

Referring more closely to the drawings, the numeral 3 represents the lower stage or the furnace of my coke oven, in general, the numerals 4 and 5 indicate the intermediate

or preliminary coking stage and the final or high quality coking oven, respectively.

The furnace 3 may be built in any convenient manner of brick lined with refractory materials having the bottom 6, the side walls 7 and the arched top 8. It may have grates to burn the fuel on—the cheapest kind of coals—or they may be simply thrown on the bottom 6 and the ashes removed intermittently or after having finished a coking operation. It may have a comparatively low front door 9 showing the openings 10 adapted to regulate the air entering the furnace. The hot gases resulting from the combustion of the fuel 11 thrown into said furnace will leave through the opening 12 in the back wall of the furnace and will enter through the channel 13 and opening 14 into the intermediate oven 4. Said oven is built somewhat similar to the furnace 3 with a bottom 15, side walls 16 and arch roof 17. In the front wall 18 of the same is provided a charging opening 19 through which the material to be coked can be thrown into the inside space 20. Said material may be any desired coal but I preferably employ a cheaper grade of it or dust and small coal. The hot combustion gases 14 entering the intermediate oven will pass over the charge to the front part of said oven and will further continue their travel through the opening 21 provided in the front part of the roof of said oven. Through the action of the hot combustion gases, the charge in the intermediate oven will be coked and the gases driven off from the same, will also leave through the opening 21 or a portion of them may be burned for further heat production, said burning depending on the amount of the air introduced into the furnace 3 through the openings 10. The final mixture of combustion and distillation gases from the intermediate oven 4 will pass through the opening 21 and continue their travel in the checkered flues 22 and 23, provided in the bottom and in the side walls of the coke oven proper, constituting the third part of my device. The gases passing through the bottom and the walls finally unite in the flues 24 and leave through the stack 25 into the atmosphere or they may be caught, washed and the valuable contents, tar and gases separated.

The upper furnace 5 also has an arched roof 26 provided with two or more charging and stamping openings 27, and a front wall 110

28 with a door opening 29. The inside space 30 of said upper oven 5 will be filled by the material to be coked which may be the dust or small particles of some suitable coal and which I preferably prepare by wetting it first, charging it through the upper opening 27 and door 29 into the oven and stamping it thereafter. Under the action of the gases in the checkered flues 22 and 23 the stamped 10 mass of the small wet coal will undergo a slow coking process and the coke produced from such inexpensive materials as mentioned, will show the highest possible qualities as to hardness, size, heating value and 15 so on.

It has been my experience with such ovens that they will produce ordinary good coke from the materials charged in the intermediate furnace in a period of about twelve 20 hours, while the full coking of the charge in the upper oven will require about forty hours, so that the intermediate oven can be charged and emptied three times, while one full operation is finished in the upper oven. 25 While the operations are going on, the two doors 19 and 29 will be well closed by heat insulating materials, like bricks and the ready products may be removed through them after said openings have been freed 30 again. In larger operations, mechanical means for removing the products and for charging the ovens may be easily installed. The gases of the upper oven may be left free to escape through the partly closed charging 35 openings 27 or a separate pipe line, as at 31, may be installed so as to catch said gases, separate their tar and oils and use these for combustion purposes thereafter. It also has been my experience with such 40 ovens that the coke produced in the upper oven is of the highest possible quality and is especially adapted for metallurgical purposes.

Having thus described my invention what 45 I claim as new and want to protect by Letters Patent is:

1. In a coke oven, three structures; the first being a furnace adapted to burn fuel therein; the second a retort adapted to receive a charge of coal and having an elongated shape, a charging door, a connection 50 to said furnace and an exit opening whereby the combustion gases of said furnace are

forced to pass through said retort and to be in contact with the material therein; a third structure, being the coking retort proper, having an elongated shape, and heating flues in its walls, one end of said heating flues being connected to the exit of said intermediate second structure and the other 60 end of the same to a stack.

2. A coke oven, comprising three superimposed structures, the lowest one being a furnace of elongated shape adapted to burn fuel therein and having an exit opening for 65 its combustion gases in the rear wall of it; a second structure built above said furnace having an elongated shape and being adapted to receive a charge of coal partly filling the same, an opening in the rear wall of said intermediate structure connected to the exit opening of said furnace and an exit opening in the roof of said second structure in the front part of the same, said second structure having appropriate charging and removing 70 openings; a third structure, being the coke oven proper, built above the second structure and materially of the same dimensions and shape as the two structures underneath the same, said coke oven proper comprising 75 a retort with charging and removing openings for the coal, coke and gases and with heating flues in its floor and side walls, the front end of said heating flues being connected with the exit openings of said second 80 structure and the rear end of said flues terminating in a stack.

3. In a coke oven, three structures; the first being a furnace adapted to burn fuel therein; the second a retort to receive a 90 charge of coal and to be heated by said furnace and by the combustion products of the same, means for allowing gaseous combustion products to pass from said furnace through said retort in contact with the material 95 therein; and the third structure being the coking retort proper adapted to receive a charge of coal and to be heated by the combined gaseous products of the first two structures and to slowly coke the charge in the 100 said third structure thereby.

In testimony whereof, I have signed my name to this specification, this 21st day of February 1923.

PARASCO ALIDJIADIS.
